PORTRABLE BURGLAR ALARM

Filed Sept. 13, 1938

Inventor:
Charles Metzler,
By Arthur H. Edward,
Attorney.

UNITED STATES PATENT OFFICE

2,284,292

PORTABLE BURGLAR ALARM

Charles Metzler, Cincinnati, Ohio

Application September 13, 1938, Serial No. 229,720

1 Claim. (Cl. 200—54)

My invention relates to burglar alarms of the type adapted to give an electrically actuated warning signal.

The principal object of the present invention is to provide an electrically operated burglar alarm of a type readily portable and which may be easily installed without previous experience or training so as to be actuated by the surreptitious opening of a hotel door or other place of temporary lodgment.

With the above and other objects in mind as will more fully hereinafter appear, my device consists of an electrically operated bell, battery and a switch which may be temporarily secured between a door and its jamb, and which, upon the opening of the door is adapted automatically to close the circuit between said battery and bell to give warning of such opening; all of said parts being adapted furthermore for enclosure in a small and readily portable housing which may be conveniently included in a traveler's grip or suitcase.

In the drawings:

Figure 1 is a perspective of my new burglar alarm showing the bell, battery and electrical connections, together with the compartment for housing the automatic switch when the device is not in use;

Figure 2 is an elevation of the automatic switch;

Figure 3 is a perspective illustrating the manner of attaching the switch;

Figure 4 is a diagram of the electrical circuit.

Figure 5 is a section showing the attachment.

The numeral 1 indicates a metal case or housing having a hinged cover 2, which may be secured when closed by locking means 3—3. The case 1 is divided into a large compartment 4 and a smaller compartment 5 by means of a longitudinal partition 6. Mounted in the compartment 4 are an electric bell 7, battery 8, which is of the small dry cell type, manually operated switch 9, binding posts 10 and 11 for connection of the automatic switch, together with the necessary electrical connections between said elements, said connections being illustrated diagrammatically in Figure 4 hereinafter more fully referred to.

The smaller compartment 5 is adapted to receive, when the device is not in use, the automatic switch 12, see Figure 2, together with the electrical cord 13 by means of which the switch 12 is connected to the binding posts 10 and 11.

The automatic switch 12 consists of two electrically conductive arms 14 and 15 which are

hinged together by means of a pintle 16; a spring 17 coiled around the pintle 16 and with its ends secured to the respective arms 14 and 15, tends normally to press said arms together so as to make contact between a terminal 18, mounted on but insulated from, arm 14 and a terminal 19 on the arm 15. The respective leads of cord 13 are connected with the terminal 18 and a binding post 20 which is electrically in circuit with the arm 14 and thus with arm 15 and terminal 19; the other ends of said leads are secured to the binding posts 10 and 11 as above set forth.

In Figure 4 the various electrical connections above described are illustrated diagrammatically. From said figure it will be seen that the manually operated switch 9 is in circuit between the battery and bell, and that such switch must first be closed before the bell becomes operable by the closure of the automatic switch 12; this switch 9 is thus provided to prevent the signal from operating when not desired for the reason that the automatic switch is normally held in closed position by means of the spring 17. When both switch 9 and switch 12 are closed however, it will be seen that a circuit from said battery, through switch 9, bell 7, binding post 10, switch 12, post 11 and back to the battery is completed, thus operating the bell.

In use, the arm 15 of the automatic switch 12 is inserted between the door and jamb, the two arms of the switch being separated against the compression of spring 17 to permit this to be done; in this position of arm 15, arm 14 rests against the door frame. The door then being closed upon arm 15, the switch is held in open position. When so set the manual switch 9 is closed. When the switches are thus set it will be observed that opening the door will release arm 15 permitting the automatic switch to close and thus to complete the battery-bell circuit.

From the foregoing it will be seen that a conveniently portable alarm device is provided which makes readily available to travelers and others occupying temporary lodgings complete protection against the surreptitious opening the door or doors to such lodgings. It will be understood that where desired a plurality of automatic switches of the type described may be provided the same to be connected in parallel in the battery-bell circuit so that the signal may be operated by either of such switches.

Having thus fully described my invention, what I claim as new and desire to secure by Letters Patent is:

In a device of the character specified a switch comprising two conductive arms, a conductive pintle upon which said arms are pivotally mounted, an electrical terminal mounted on one of said arms, a second terminal mounted on the other arm, means for insulating said second terminal from the arm on which it is mounted, the terminal bearing end of one of said arms being adapted to be inserted and held between movable and immovable building members and the terminal bearing end of the other arm being adapted to rest against the surface of one of said building

members, whereby angularly disposed planes of one of said members are slidably engaged by said arms, a spring mounted on said pintle with its respective ends attached to the respective arms so as normally to force the terminal bearing ends of said arms together whereby upon the movement of said movable building member, said ends are compressed so as to force said arms away from said members and to cause said terminals to contact.

CHARLES METZLER.
